ABSTRACT OF THE DISCLOSURE

A retarding device for the delivery end of a printing machine for printing a flexible material such as paper in the form of a web or web-portion, comprising, upstream of a take-off station for sheets or sections of sheets, a rotary take-up cylinder having retractable means for entraining the sections or sheets by their forward portions. This cylinder has at least one retarding element rotated in the opposite direction from the cylinder and projecting periodically outside the cylinder periphery, in a predetermined angular position of the cylinder, and this retarding element co-operates in this angular position of the cylinder, with a rotary roller outside the cylinder, to retain the sections or sheets by their trailing portions.

The invention relates to a retarding device for the delivery end of a printing machine.

In machines for printing a flexible material such as paper in the form of a web or web portion, printed sheets, or the sections formed by cutting and folding the printed sheets, are usually retarded by transferring them from one rotary cylinder to another with a lower peripheral speed. This retarding method may involve transfers to a third or even a fourth cylinder, the last retarding step being carried out by means of a drum into which the sections or sheets are projected by the last retarding cylinder and from which they are extracted and released onto a machine delivery table.

If transfer of the sections or sheets is by means of grippers, these grippers are in front of the sections or sheets in the direction of movement, and retardation is substantially instantaneous. The trailing ends of the sections or sheets tend to approach the forward portions, causing crumpling if the step-down ratio between two cylinders is too high. This ratio is therefore limited in practice to approximately 35%. If transfer is by means of spikes, the difference in the peripheral speed between two successive cylinders must be approximately 25% to prevent tearing.

A disadvantage of using a plurality of retarding cylinders is that the resulting device is bulky and expensive.

The object of the invention is to provide a retarding device in which a single retarding cylinder gives step-down ratios at least twice the usual ratios between successive retarding cylinders, without risk of crumpling or tearing.

The retarding device according to the invention has, before a take-off station for sheets or sections of sheets, a rotary take-up cylinder having retractable means for entraining the forward portions of the sections or sheets, this cylinder has at least one retarding element rotated in the opposite direction from the cylinder and projecting periodically outside the cylinder periphery near and downstream of the trailing edge of the sections or sheets, in a predetermined angular position of the cylinder, and this retarding element cooperates in this angular position of the cylinder with a rotary cooperating roller which is outside the cylinder and whose peripheral speed is equal to

the residual tangential speed of the retarding element, to retain the trailing portion of the sections or sheets at this resultant tangential speed.

A retarding device embodying the invention is shown diagrammatically in the accompanying drawings and will now be described, by way of example only.

In the drawings:

FIGURES 1, 2 and 3 show the retarding device diagrammatically in three successive positions, illustrating the beginning of a retarding action, the retarding period and the end of the retarding action; and

FIGURE 4 is a transverse section on a larger scale through a cooperating roller.

The retarding device has a take-up cylinder 1 with retractable spikes 2 for entraining the front portions of sections 3. These spikes are controlled by known means (not shown).

The cylinder 1 carries two retaining elements consisting of bars 4 mounted on two axes 5 parallel to the axis 6 of the cylinder and diametrically opposite each other relative to this axis. The bars 4 are constantly rotated in the opposite direction from the cylinder 1 by planet gears 7 engaging a stationary sun gear 8, and by gears 9 keyed on the bars 4.

Each bar 4 has a portion with a rounded outline 4a or a plurality of fingers forming such an outline, which, with each revolution of the bar project a distance d outside the periphery of the cylinder 1, through openings 1a.

The step-up ratio is such that each of the two bars 4 carries out a whole number of turns about its axis 5 for each revolution of the cylinder 1. In the embodiment shown, with two bars 4, each of these bars turns twice about its axis 5.

Suitable selection of the distance E between the axes 5, 6 and of the eccentricity D of the rounded portions 4a relative to the pivot 5 gives at the top of these rounded portions—in their plane of alignment X—X with the axes 5, 6 (FIGURE 2)—a resultant tangential speed Va lower than the tangential speed Vb on the periphery of the cylinder 1, in a predetermined ratio such as 2:5, for example.

In the plane of alignment X—X lies a co-operating roller 10 rotated in the opposite direction from the cylinder 1 and having push rods 11 supported on springs 12 (FIGURE 4). The step-up ratio between the cylinder 1 and roller 10 is such that the tangential speed at the free end of the push-rod 11 is equal to the resultant tangential speed Va.

Operation is as follows:

A section 3, shown at the top of FIGURE 1, has been taken off a preceding cylinder (not shown) by the cylinder 1 and is entrained by the corresponding spikes 2. Another section 3 is already engaged between the bar 4 and roller 10 and is being released by other spikes 2. The trailing end of this section, hitherto entrained at the peripheral speed Vb of the cylinder 1, is then gripped near the plane X—X by the rounded portion 4a and by the push-rod 11 of the roller 10 (FIGURE 2), and its speed is brought to value Va which will be its delivery speed (FIGURE 3) as it approaches the take-off station or possibly a take-off drum (not shown).

The retaining action exerted on the trailing portion of the section keeps the section taut and prevents it from crumpling when released. Since the rotating action does not occur until after the spikes release the section, there is no risk of tearing being caused by the spikes.

Obviously, the retarding device just described can be modified and any useful accessory may be added to it without exceeding the scope of the invention. For example, the take-up cylinder may be adapted to take up a larger number of sections or sheets and carry a larger number of rotary retaining elements, associated with a single co-

operating roller or with two co-operating retaining rollers acting alternately. Also, the retarding element, instead of having one portion projecting periodically from the take-up cylinder, could be a cylinder whose periphery constantly projects.

What I claim is:

1. A retarding device for the delivery end of printing machines for printing a flexible material such as paper in the form of a web or web portion, characterised in that it has, before a take-off station for sheets or sections of sheets, a rotary take-up cylinder having retractable means for entraining the forward portions of the sections or sheets, this cylinder has at least one retarding element rotated in the opposite direction from the cylinder and projecting periodically outside the cylinder periphery 15 near and downstream of the trailing edge of the sections or sheets, in a predetermined angular position of the cylinder, a rotary co-operating roller, and this retarding element co-operates in this angular position of the cylinder with said rotary co-operating roller which is outside the cylinder and whose peripheral speed is equal to the residual tangential speed of the retarding element, to retain the trailing portion of the sections or sheets at this tangential speed. 20

2. A retarding device as claimed in claim 1, characterised in that each of the retarding elements carried by the cylinder is inside the cylinder and is rotated about an axis parallel to the cylinder axis by means of a planet gear 5 carried by the cylinder and engaging continuously with a fixed gear coaxial with the cylinder.

3. A retarding device as claimed in claim 1, characterised in that on each of the retarding elements carried by the cylinder an eccentric portion periodically projecting outside the cylinder periphery has a rounded outline whose generatrices are parallel to that of the cylinder.

4. A retarding device as claimed in claim 1, characterised in that on said rotary co-operating roller outside the cylinder the retaining element which co-operates with the retarding elements carried by the cylinder to retain the trailing portion of the sections or sheets is subject to a resilient member which urges it to bear on the sections or sheets.
